[57] ABSTRACT

A fuel injection valve comprising a nozzle body having an inlet and an outlet and a cavity therebetween, a nozzle needle arranged in said cavity and spaced apart from said nozzle body to define an annular space therebetween for forming a fluid passage, said nozzle needle being mounted for reciprocating movement between opened and closed positions in said cavity, said nozzle body being sealed off at one end thereof by stop means, said nozzle needle at the end thereof adjacent said stop means being connected to a diaphragm arranged in said stop means, resilient guide means arranged in said nozzle body at the other end thereof from said stop means, said diaphragm and resilient guide means being mounted in said housing for securing said nozzle needle in a desired spatial relationship in said cavity whereby pressure applied onto said diaphragm acts to move said needle in said cavity between said open and closed position.

FUEL INJECTION VALVE

This invention relates to an injection valve and more particularly relates to an injection valve for use in an internal combustion engine.

The fuel injection valve of the type in accordance with the invention comprise a housing composed of a nozzle chamber and spring chamber sealed off from one another. The nozzle chamber includes a fluid venting port, a nozzle needle which is spring biased to maintain the venting port normally in closed position, upon reaching a predetermined excess of pressure the needle is moved against the spring bias to position the fluid port in open position and through the passage of fluid therethrough relieving the pressure build-up within said nozzle chamber whereupon the needle is returned to its position for closing off the venting port.

The known injection valves are provided with rigid needle guides and have very little clearance between the nozzle body and the nozzle needle. The nozzle needle serves in this type of construction as the closing member. The sealing off of the nozzle chamber from the spring chamber is effected in these known valves by resilient elements, in which connection the resilient members also serve as guides. The resilient members are in the main constructed of a rubber material which can be either natural or synthetic and are generally secured in the desired position by vulcanization techniques. The diaphragms are constructed as disc-shaped members and can be made either from rubber or metal. The diaphragms are arranged between the nozzle chamber and the spring chamber and are supported in part by specially molded and shaped parts, the diaphragms resting thereon and conforming in shape thereto, the aforesaid parts serving also to prevent penetration of the diaphragm by the nozzle needles.

Other constructions are known in which the sealing is brought about by means of alternately arranged rubber and metal discs. The diaphragm in this type of construction is secured into position by the clamping action of the various parts when screwed together.

The rigid needle guides are required to be prepared by extremely careful mechanical procedures. Impurities in the fuel or slight deformations in the nozzle body as for example arises in poor assembly or installation result in a premature wearing out of the guide and therewith failure of the valve. The guides in addition exert a braking effect on the nozzle needles because of the tight fit. If on the other hand greater clearances are provided, losses due to oil leaks are unavoidable. The rapidly changing high pressures combined with the heat generated in use result in a rapid wearing out of the diaphragms and in particular the diaphragms become porous at the points of contact thereof with the needle and inevitably break or tear after some time. Oil losses and failure of the device are the result.

In order to avoid the use of rigid needle guides, the known injection nozzles have frequently been provided with specially constructed guides and/or transmissions. These special constructions generally involve an increase in the number of parts and particularly of the moving parts in the valve and therewith also an increase in the dimensions of the injection valve and the manufacturing costs. Furthermore, the error factor is likewise increased.

It is an object of this invention to provide a fuel injection valve free of the disadvantages associated with the known constructions.

Another object of this invention is to provide an injection valve in which the essential parts and in particular the moving parts are kept to a minimum.

Still another object of the invention is to provide a valve in which the spring chamber and nozzle chamber are separated one from the other in an entirely leak proof manner.

Yet another object of the invention is to provide a fuel injection valve in which the needle is not unnecessarily loaded or damaged by the guide means.

These and other objects and advantages of the invention will appear from the following description which is accompanied by the drawing which shows a vertical sectional view of

a fuel injection valve embodying the principals of the invention.

In accordance with the invention a fuel injection valve is provided which is composed of a nozzle body having an inlet and an outlet for fluid and cavity therebetween, a nozzle needle is arranged in the cavity and spaced apart from the nozzle body so as to define an annular space therebetween which serves as a fluid passage, the nozzle needle is mounted in the cavity for reciprocating movement between open and closed positions, the nozzle body is sealed off at one end thereof by a stop means, the nozzle needle at the end thereof adjacent said stop means is connected to a diaphragm which is arranged in the stop means, resilient means are provided in the nozzle body at the end thereof opposite from the stop means, the diaphragm and resilient guide means being mounted in the nozzle housing for securing the nozzle needle in a desired spatial relationship in the nozzle cavity. Pressure applied onto the diaphragm in the aforesaid construction acts to move the nozzle needle between an open and closed position.

In accordance with the invention the nozzle needle is arranged in the nozzle body in spaced apart relationship so as to define an annular space therebetween of comparatively great size. The annular space serves also as the fuel conduit for the valve. At the bottommost end of the nozzle body there is arranged a packing assembly which includes a packing cone, the latter being dimensioned to ensure a tight fit between the needle point and the injection orifice or opening. There is arranged in the nozzle body above the packing assembly of resilient guide piece which is preferably made of a synthetic or plast material. To the other or topmost end of the nozzle body, there is screwed a bushing having a stop mounted therein. The uppermost end of the nozzle needle is incorporated into a membrane-like rubber of synthetic body hereinafter referred to as a diaphragm. In order to increase the stability thereof, a metal insert is arranged in the diaphragm the same preferably being secured in place by vulcanization. By tightly screwing the bushing onto the nozzle body, the stop is urged in the direction of the nozzle body and the diaphragm is thereby secured in a leak proof manner between the nozzle body and the stop and at the same time, the diaphragm is centered. The stop is so constructed that all sides of the diaphragm can press against it. A metal disc is secured to the diaphragm and serves for absorbing the pressure exerted by the spring and to transmit the same to the diaphragm. The spring force is directly transmitted to a support which is inserted into an opening in the stop and which is disposed on the metal plate. The bushing is sealed by a pressure adjusting screw which acts on a spring plate and by means of which the opening pressure of the valve can be adjusted. In order to protect the entire device, the upper end of the bushing is provided with a plastic cap.

The fuel injection valve works as follows:

When the force resulting from the pressure in the nozzle chamber of the construction of the invention corresponds to the force exerted by the spring, the needle begins to rise. The cross section of the packing cone which is thereby exposed is thusly exposed to fuel pressure and this force acts on the needle in initiating its upward movement. The pressure acts also at the same time on the diaphragm urging it against the stop in the bushing. A pulling force is exerted on the needle which is vulcanized at its end portion to the interior of the diaphragm. The diaphragm and the stop in the bushing are preferably so constructed that friction between these two parts in actual operation is very low. As the needle is guided elastically only at its two ends, it can adjust itself at any time automatically to the conical seat in the packing assembly. The friction between the needle and the guide members is very low because the needle is provided with a sufficient degree of freedom of movement. The moving mass is reduced to a minimum. The same holds true for the number of moving parts. The manufacture of the structural components involved requires no unusual expenditures. The production of the injection valve according to the invention can be carried out using in the main commercially available parts. The failure of the injection valve due to

jamming of the needle or by guides which have been damaged in operation is substantially eliminated. There are no losses due to oil leakage in that the nozzle chamber is completely sealed off in the nozzle body.

The invention will be further described by reference to the drawing in which an embodiment of the invention has been shown.

A nozzle needle 8 is arranged in a nozzle body 1 so as to provide a considerable clearance space therebetween. At the bottommost end of the nozzle body 1, there is arranged a packing assembly 3 which is provided with a packing cone 14 for the nozzle needle point and the injection orifices. Above the packing assembly 3 in the nozzle body 1, there is arranged a resilient guide piece 9 preferably formed from a plastic or other synthetic material. At the other end of the nozzle body 1, there is secured by screwing a bushing 4 in which there is arranged a stop 6. The upper end of the nozzle needle is vulcanized or compressed into a membrane like body preferably made of rubber or of a synthetic material and which is referred to herein as a diaphragm 5. The stop 6 is so constructed that all sides of the diaphragm 5 can press onto the stop. In order to increase the stability of the diaphragm a metal insert 7 is vulcanized into the diaphragm 5. When the bushing 4 is secured by the screwing thereof onto the nozzle body, the stop 6 is urged in the direction of nozzle body and the diaphragm 5 is sealed between the nozzle body 1 and the stop 6, and is centered at the same time. The nozzle chamber in the nozzle body 1 is thus made completely leak proof. A metal disc 10 is arranged between the stop 6 and the diaphragm 5 and serves to absorb the pressure of the spring 11 and transmit it onto the diaphragm 5. The spring force is first absorbed by a support 15 which protrudes through an opening in the stop 6 and is further transmitted therefrom to the metal disc 9. At the top, the bushing 4 is terminated by a pressure adjusting screw 12 which passes onto a spring plate 13 and by means of which the opening pressure of the valve can be regulated. For additional protection, the end of the bushing 4 which carries the pressure adjusting screw 12 is covered over with a plastic cap 16. The fuel is introduced through the pressure inlet conduit 2 into the nozzle body 1 and flows through the space established between the nozzle body 1 and the nozzle needle 8. Due to the pressure built up in the nozzle chamber, the nozzle needle 8 is lifted from its seat in the packing cone 14 and the injection process started up. The spring 11 acts to counteract this venting or opening of the injection orifice and as soon as a pressure drop has taken place in the nozzle chamber by virtue of the jetting or venting of the fuel the nozzle needle 8 is urged back

by the spring 11 into the packing cone 14.

What is claimed is:

1. A fuel injection valve comprising a nozzle body having an inlet and an outlet and a cavity therebetween, a nozzle needle arranged in said cavity and spaced apart from said nozzle body to define an annular space therebetween for forming a fluid passage, said nozzle needle being mounted in said cavity for reciprocating movement between open and closed positions, said nozzle body being sealed off at one end thereof by stop means, said nozzle needle at the end thereof adjacent said stop means being connected to a diaphragm arranged in said stop means, resilient guide means being arranged in said nozzle body at the other end thereof from said stop means, said diaphragm and resilient guide means being mounted in said housing for securing said nozzle needle in a desired spatial relationship in said cavity, whereby pressure applied onto said diaphragm causes said nozzle needle to move in said nozzle body between said open and closed positions.
2. A fuel injection valve according to claim 1, said nozzle needle being connected at its upper end to said diaphragm by vulcanization.
3. A fuel injection valve according to claim 1, said nozzle needle being connected at its upper end to said diaphragm by compression.
4. A fuel injection valve according to claim 1 wherein said diaphragm is made of natural rubber, synthetic rubber or a plastic material.
5. A fuel injection valve according to claim 1 wherein said diaphragm and said stop means are constructed so as to conform to one another and to permit all of the external surfaces of the diaphragm to press upon the abutting surfaces of said stop means.
6. A fuel injection valve according to claim 1 wherein said stop means limits the extension of said diaphragm.
7. A fuel injection valve according to claim 1 wherein said stop means is mounted in a bushing.
8. A fuel injection valve according to claim 7 including a pressure regulating screw arranged at the top of said bushing for regulating the opening pressure of said valve.
9. A fuel injection valve according to claim 1 including spring means arranged for urging said diaphragm in a downward direction.
10. A fuel injection valve according to claim 9 wherein a metal disc is arranged between said stop and said diaphragm, the force of said spring being transmitted through said metal disc to said diaphragm.
